UNITED STATES PATENT OFFICE.

WALTER P. SCOFIELD, OF WOODROW, FLORIDA, ASSIGNOR OF ONE-HALF TO DAVID C. GILLETT, OF TAMPA, FLORIDA.

FENCE.

1,228,062.

Specification of Letters Patent.

Patented May 29, 1917.

Application filed June 3, 1916. Serial No. 101,584.

To all whom it may concern:

Be it known that I, WALTER P. SCOFIELD, a citizen of the United States, residing at Woodrow, in the county of Lee and State 5 of Florida, have invented certain new and useful Improvements in Fences; and I do hereby declare the following to be a full, clear, and exact description of the invention, such as will enable others skilled in the art 10 to which it appertains to make and use the same.

The present invention relates to improvements in fences, and has for an object to provide an improved fence which will be constructed of band metal arranged to be secured to fence posts as now done in the case 15 of wire mesh fencing.

Broadly stated, the improved fence embodies line bands of flat thin metal secured 20 to vertical stays of similar construction; such bands and stays being spaced apart and secured together by improved joints formed from the metal of the bands and stays without separate parts, the bands and stays thus 25 making a mesh-work of ornamental nature ready to be secured to the fence posts.

The improved fence as thus constructed is adapted to be rendered capable of expansion 30 and contraction by including in the line bands and stays bent or doubled portions, the metal being preferably of some elasticity for causing contraction after the expanding strain has been removed.

A further object of the present invention 35 resides in providing and constructing an improved metallic fence, the elements of which can be formed by present machinery as now installed in factories, and which can be made cheaply and will be of increased durability 40 and strength over wire or other fences as now built.

In the accompanying drawings forming a part of this application, and in which similar reference symbols indicate corresponding 45 parts in the several views:

Figure 1 is a perspective view of a portion of an improved fence as constructed in accordance with the present invention.

Fig. 2 is a vertical sectional view taken on 50 the line 2—2 in Fig. 1.

Fig. 3 is a perspective view of the abutting ends of adjacent line bands illustrating a connection therefor.

Fig. 4 is a similar view showing the connection as effected.

Fig. 5 is a fragmentary perspective view of a modified form of band; and

Fig. 6 is a fragmentary perspective view of a plain fence without barbs.

Referring more particularly to the drawings, 1 designates the line bands and 2 the vertical stays. The line bands 1, as shown to advantage in Fig. 1, are passed alternately to one side and the other of the vertical stays 2; while the latter are similarly passed 65 alternately to opposite sides of the line bands.

Where the line bands 1 and stays 2 cross each other, they are jointed together preferably by the connection shown in the drawings, which involves no separate parts, but which is formed solely of the material of the fencing. This connection includes depressions 3 formed in the stays 2 to receive heads 4 pressed out of the line bands 1. The 70 line bands 1 are clamped with the heads 4 occupying the depressions 3 by tongues 5 and 6, stamped out of the material of the stays 2 and bent over in opposite directions, for which see Figs. 1 and 2. In thus stamping 80 out the tongues 5 and 6, openings 7 and 8 are made in the stays 2, which may receive nails or other fastening means, whereby the fencing is secured to posts of ordinary construction.

It is to be understood, of course, that while, in the drawings, the depressions 3 are shown in the stays 2, the heads 4 in the line bands 1 and the tongues 5 and 6 stamped out of the stays, these parts may be reversed so 90 that the tongues may be stamped and bent from the line bands 1, and the other elements modified accordingly.

There are bent or buckled portions 9 and 10, respectively, in the line bands 1 and stays 95 2 for the purpose of imparting adjustability and the capacity to contract and expand, the metal of the parts being for this purpose preferably slightly resilient to exert sufficient stress to contract the fence, through the 100 portions 9 and 10 after any strain that may have been imposed thereon has been relieved.

At the upper ends of the vertical stays 2 and beyond the uppermost line band 1, said 105 stays are cut and bent to provide end lugs 11 and 12, overturned above the uppermost band 1 and intermediate barbs 13 and 14 one of which stands upwardly, while the other is bent over at right angles to project hori- 110

zontally. It is obvious that barbs may be stamped from other portions of the fence, if desired.

Referring now more particularly to Figs. 3 and 4, a preferred form of connecting the ends of the line bands 1 is here shown to consist of rectangular or other depressions 15, pressed in the end 16 of one of the line bands for receiving similarly shaped heads 17 formed on the end of the adjacent line band 18. The end of the line band 18 is formed with a series of spaced notches or recesses 19 along both the upper and lower edges; and when the bands 16 and 18 are assembled as in Fig. 4, lugs 20 on the end 16 are fitted through said notches 19 and clenched over on the free face of the band 18, as shown at 21 in Fig. 4.

In Fig. 5 is shown at 18' a modified form 20 of fence band, in which the same may be made of metal, flat, thin and flexible, as in the case of the bands shown in the preferred form, but the longitudinal edges of which are preferably turned over or otherwise reinforced, as indicated at 19' and 20', to impart additional strength and durability to the fence.

Having reference now to Fig. 6, 22 indicates the uppermost line band of a fence, 30 and 23 one of the stays which is connected thereto by the head and socket joint, as indicated in dotted lines at 24. In this form of the invention the barbs are dispensed with and the fence made plain by turning 35 over the extremity 25 of the stay 23, without slitting or dividing the same or bending any barbs therefrom. The end 25 is preferably of a length to extend over the joint 24, concealing and effectually locking the bands 40 and stays together.

It will be appreciated from the foregoing that the fence, as above described, may be formed complete at the factory and rolled up for shipment, as is the practice with 45 wire fencing, or the line bands and stays may be manufactured without assembling and connecting the same and transported to the field where they may be connected and set up without any great amount of trouble 50 or expense; and when completed form an attractive, durable, and strong fence, which can be readily seen and is not deceptive, as are wire fences now so generally in use.

It is obvious that those skilled in the art 55 may vary the details of construction and arrangements of parts without departing from the spirit of my invention, and therefore I do not wish to be limited to such features except as may be required by the 60 claims.

I claim:

1. In a fence, line bands, stays crossing said line bands, heads and sockets formed between said bands and stays, and means 65 for connecting said bands and stays to hold

the heads in said sockets including tongues punched from one series of said members and overturned rearwardly against the members of the other series, substantially as described.

2. In a fence, line bands, stays crossing said line bands, heads and sockets formed between said bands and stays, and tongues punched from said stays and being overturned in opposite directions against said 75 bands leaving openings for receiving fastening means, substantially as described.

3. In a fence, line bands having notches at one end thereof, complementary rectangular heads and sockets stamped from said bands, and lugs bent transversely from the opposite end of the band and inter-engaged with said notches, substantially as described.

4. In a fence, line bands, stays crossing said line bands and secured thereto, loops 85 bent in said stays and bands for permitting of contraction and expansion, lugs bent from one end of each of said bands and folded over on lines of flexure extending longitudinally of the band and clamped down 90 against the adjacent end of the next band, substantially as described.

5. In a fence, stays, line bands crossing said stays, loops bent in said stays and bands for permitting of contraction and expansion and joints between said bands and stays including heads, sockets occupied by said heads, and tongues punched from said stays and bent over in pairs in opposite directions rearwardly to clamp said bands, substantially as described.

6. In a fence, stays, line bands crossing said stays, loops bent in said bands and stays for permitting of expansion and contraction, means connecting said bands and stays including sockets on said bands, heads on said stays fitting said sockets, tongues punched from said stays and bent over rearwardly in opposite directions to clamp said bands with the heads occupying said sockets and leaving openings to receive fastening means, and lugs punched from one end of each of said line bands and adapted to be bent over transversely with their bases extending longitudinally of the band and clenched against 110 the end of the next adjacent band, substantially as described.

7. In a fence, line bands, stays secured to said line bands and projecting above and below the uppermost and lowermost line 120 band, barbs formed on the projecting upper and lower ends of said stays, lugs also formed on the stay ends and being bent over and clenched against the adjacent line bands, loops bent from said bands and stays, means 125 for joining said bands and stays including sockets, heads occupying said sockets, and tongues punched from one series of said members and overturned against the other series, and means for uniting the ends of the 130

line bands including heads, sockets occupied by said heads and lugs bent transversely from one end and clenched over against the end of the next adjacent band, substantially 5 as described.

8. An improved fence including flat metal bands, flat metal stays, said bands and stays being passed alternately to opposite sides of one another, doubled portions in said 10 bands and stays for admitting of contraction and expansion, means for connecting said bands and stays including depressions, heads fitting in said depressions and tongues

for holding the members with the depressions and heads engaging, and means for 15 uniting the ends of adjacent bands including heads and sockets formed in said band ends, one of said bands having series of notches therein, and series of lugs bent from the 20 other of said bands and received into the notches in the companion band, said lugs being clenched over on the free face of the companion band, substantially as described.

In testimony whereof, I affix my signature.

WALTER P. SCOFIELD.
